SPARK PLUG

Gilbert C. Barnes, Manchester, Conn., assignor to
 United Aircraft Corporation, East Hartford,
 Conn., a corporation of Delaware

Application April 24, 1940, Serial No. 331,435

7 Claims. (Cl. 123—169)

This invention relates to improvements in spark plugs for internal combustion engines and has for an object the provision of means for automatically controlling the temperature of the 5 sparking end of a spark plug of the character indicated.

A somewhat more specific object resides in the provision in a spark plug of the character indicated of means for automatically controlling the 10 heat dissipation from the firing end of the plug in accordance with the amount of heat absorbed by the plug.

Other objects and advantages will be more particularly pointed out hereinafter or will be 15 come apparent as the description proceeds.

In the accompanying drawing, in which like reference numerals are used to designate similar parts throughout, there is illustrated a suitable 20 mechanical arrangement for the purpose of disclosing the invention. The drawing, however, is for the purpose of illustration only and is not to be taken as limiting or restricting the invention as it will be apparent to those skilled in the 25 art that various changes in the illustrated construction may be resorted to without in any way exceeding the scope of the invention.

In the drawing, the single figure is a vertical 30 sectional view through a spark plug constructed according to the invention.

Referring to the drawing in detail, the numeral 10 generally indicates a shank or base portion having external screw threads 12 on one end portion for engagement with the screw threads in the spark plug aperture in an engine cylinder 35 head, internal screw threads 14 at the opposite end for the reception of the external screw threads provided on a gland nut 16, an annular shoulder 18 for compressing a plug sealing gasket and a polygonal wrench reception portion 20.

The gland nut 16 has a polygonal wrench 40 reception portion 22 and a beveled end portion 24 at the opposite end which cooperates with a beveled internal shoulder 26 in the base member 10 to compress a packing 28 to provide a fluid tight 45 seal between the members 10 and 16.

Within the members 16 and 18 there is a substantially coaxial hollow core member 30 provided at one end with a center electrode 32 and surrounded at the opposite end by a cable terminal 34. This center electrode may be surrounded by a sleeve 36 of insulating material between the terminal 34 and a washer 38 disposed against an annular shoulder 40 on the end portion of the electrode 32. Insulating material 42, 55 formed in one or more pieces, is applied between

the sleeve 36 and the gland 16 and may be secured to or formed integrally with the sleeve and may rest upon an annular internal shoulder 44 provided in the gland 16 to restrain the center electrode against lengthwise movement relative 5 to the supporting portion of the spark plug. A body of insulating material 46 may surround the lower portion of the sleeve 36 and bear at its opposite ends against the annular shoulder 44 and the washer 38 and another body 48 of insulating 10 material may surround the upper portion of the sleeve 36 and bear at its end on the top of the gland 16 and the under surface of the terminal 34, these bodies of insulating materials serving 15 additionally to locate the center electrode in the supporting structure against lengthwise movement relative thereto.

Within the bore of the hollow center electrode 32 there is disposed a stack of transversely arranged copper discs 50 having their adjacent 20 faces in contact with each other, one end of the stack being in contact with the firing point of the center electrode and the other end being in contact with the inner end of a plug 52 screw threaded into the outer or upper end of the center electrode. The material of the center electrode has a somewhat different coefficient of heat expansion than the expansion coefficient of the copper discs, the coefficient of the discs preferably being somewhat greater than the coefficient 30 of heat expansion of the electrode, and the plug 52 is adjusted to apply a very slight predetermined pressure to the stack of discs when the spark plug is cold. With this arrangement, when the plug is cold there will be only a light 35 contacting pressure between the adjacent surfaces of the discs comprising the stack within the hollow electrode and the stack will, therefore, be a relatively poor conductor of heat. As the plug heats up, however, due to the unequal 40 coefficients of heat expansion, the stack will expand somewhat more rapidly than the electrode and the pressure between the adjacent discs will increase and the heat conduction capacity of the stack will correspondingly increase so that heat 45 will be more rapidly removed from the firing point end of the center electrode and dissipated from the end of the plug carrying the terminal 34.

With this arrangement the firing end of the 50 plug, which projects within the combustion chamber of the engine cylinder, will heat up very rapidly to its operating temperature since most of the heat of the first few explosions will remain 55 in the firing end of the plug, but as soon as the 55

temperature of the firing end has reached the optimum operating temperature the stack of discs will have expanded until the stack functions as a good heat conductor and thereafter 5 removes the excess heat from the firing end of the plug at a rate which prevents the firing end from exceeding the desired operating temperature.

While copper has been mentioned as a suitable 10 material for the discs and it is well known that some steel alloy such as nickel or tungsten steel are usually used for the center electrodes of spark plugs, it is to be understood that the invention is not to be limited to these particular 15 materials but that various other combinations may be used which will perform substantially the same function, the principal consideration being that the material of the discs should have a somewhat greater coefficient of heat expansion 20 than the material of the center electrode and that the material of the discs should be a relatively efficient conductor of heat.

While a particular structural embodiment has been hereinabove described and illustrated in the 25 accompanying drawing, it is to be understood that the invention is not limited to the particular embodiment so described and illustrated, but that such changes in the size, shape and arrangement of the various parts may be resorted to as 30 come within the scope of the subjoined claims.

Having now described the invention so that others skilled in the art may clearly understand the same, what it is desired to secure by Letters Patent is as follows:

35 1. In an engine spark plug, a center electrode having a longitudinal bore therein, and a stack

of plates of a material having a relatively high heat conductivity disposed in said bore.

2. In an engine spark plug, a center electrode having a longitudinal bore therein, and a stack of discs of a material having a relatively high 5 heat conductivity and a coefficient of heat expansion greater than the heat expansion coefficient of said center electrode disposed in said bore, and a relatively fixed abutment for each end of said stack.

10 3. Temperature regulating means for a spark plug having a hollow center electrode comprising, a stack of metal plates in said electrode of a material having a heat expansion coefficient different from the heat expansion coefficient of 15 the material of said electrode, and abutments for the ends of said stack spaced to maintain consecutive plates in loose contact with each other when said spark plug is cold.

4. The arrangement as set forth in claim 3 in 20 which at least one of said abutments is adjustable.

25 5. The arrangement as set forth in claim 3 in which the closed end of said hollow center electrode constitutes one of said abutments and the other abutment comprises a plug screw threaded into the open end of said electrode.

6. The arrangement as set forth in claim 3 in 30 which the main ingredient of said plates is copper.

7. The arrangement as set forth in claim 3 including a cable terminal on the outer end of said center electrode and in which said stack extends to a location within said cable terminal.

35 GILBERT C. BARNES.
